CLAIM

The ornamental design for a combined chatter stick percussion instrument and mount therefor, as shown and described.

DESCRIPTION

FIG. 1 is a perspective view of a chatter stick percussion instrument showing my new design;

FIG. 2 is an elevational view thereof, the side opposite being a mirror image of the side shown in FIG. 2, with the exception of the mounting bolt;

FIG. 3 is an end elevational view thereof;

FIG. 4 is a top plan view thereof; and,

FIG. 5 is a bottom plan view thereof.

FIG. 1

FIG. 3

FIG. 2
